UNITED STATES PATENT OFFICE.

EVERT ASPFORS, OF FLOODWOOD, MINNESOTA.

HARROW.

1,109,813.

Specification of Letters Patent. Patented Sept. 8, 1914.

Application filed April 17, 1913. Serial No. 761,783.

To all whom it may concern:

Be it known that I, EVERETT ASPFORS, a citizen of the United States, residing at Floodwood, in the county of St. Louis and State 5 of Minnesota, have invented certain new and useful Improvements in Harrows, of which the following is a specification.

This invention relates to new and useful improvements in harrows and more particularly to the class having rotary teeth, or the like.

An object of this invention is to simplify devices of this character making them portable and of such construction that a novice 15 can readily assemble them together or take them apart.

Another object of this invention is to supply a device that can be utilized as a harrow during the summer months, and can also be 20 used as a sled in the winter.

With the above and other objects in view this invention resides in the novel features of construction, formation, combinations and arrangements of parts to be hereinafter 25 more fully described, claimed and illustrated in the accompanying drawings in which:—

Figure 1, is a side elevation of my improved harrow, Fig. 2, is a longitudinal view of the same taken on the line 2—2 of Fig. 5, Fig. 3, is a perspective view of the upper frame section of my harrow, Fig. 4, is a perspective view of the runners of my harrow, Fig. 5, is a bottom plan view of my improved harrow, Fig. 6, is a side elevation 30 of one of the shaft bearings, and Fig. 7, is a front elevation of the same.

Referring to the accompanying drawings by similar characters of reference the numeral 10 denotes in general my improved 40 harrow, which is composed of an upper rectangular frame 11 and a lower rectangular frame 12. The upper frame 11 has enlarged apertures 13 formed therein for the reception of the bolts 14 which pass through the 45 covering or platform 15 forming the top of the harrow, while the rear and front ends of the rectangular frame 11 are bent in a downward position forming legs 16 and 17 and are joined by transverse bars 18 and 19, 50 the transverse bar 18 having formed midway thereon a draft attachment 20. The frame 11 is bent into this formation so as to give the platform 15 an elevation so that

the same will not contact with the mechanism of the harrow, thus doing away with 55 numerous braces, and at the same time giving the harrow when used as a sled a spring effect. The lower frame work 12 is practically of the same construction, except that its front and rear ends are bent in an upward direction forming legs 21 and 22 the same being also connected by transverse bars 23 and 24, the transverse bar 23 having formed midway thereon a draft attachment 25 corresponding with that of the bar 18 of 60 the upper frame. The upper frame 11 has also formed in its legs 16 and 17 enlarged apertures 26 and 27 which correspond with the apertures 28 and 29 formed in the legs 21 and 22 of the lower frame 12. Through 65 these apertures pass bolts 30 and 31 which securely hold the upper frame 11 and lower frame 12 together, while the longitudinal bar 32 of the lower frame 12 constitutes a runner when it is desired to use the harrow 70 as a sled for hauling purposes. Secured to this bar 32 at suitable intervals are bearings 33 having apertures 34 formed therein for the reception of the ends of the horizontal shafts 35—36 and 37. These bearings 33 75 are grooved as at 38 as clearly shown by Fig. 6 of the accompanying drawings, the grooved portion receiving a U-bolt 39 which passes around the end of the shaft, its ends then passing through apertures 40 80 formed in the bar 32 and securely held in 85 position by nuts 41.

The shafts 35—36 and 37 have secured to them at suitable intervals rotary teeth 42 which are secured to the shaft by means of 90 a set screw 43, these shafts are held against displacement by collars 44 secured thereto by a suitable means. These rotary teeth 42 are so arranged that when the harrow is in operation the teeth 42 will not contact 95 at all. The set of teeth 42 mounted on the shaft 35 breaking the soil first, while those mounted on the shaft 36 travel intermediate the path of those mounted on shaft 35 and turn the soil that has not been molested by 100 the preceding set of teeth on the shaft 35, while those mounted on the shaft 37 travel in the path of those mounted on the shaft 35, thus turning any particles of soil that may not have been turned by the preceding 105 shaft 35.

Having thus fully described this invention what I claim as new and desire to protect by Letters Patent is:—

5 The combination in a harrow of a plurality of rectangular frames having draft attachments formed thereon, legs formed upon the said frames and having apertures formed therein, bars connecting the said

legs, the lower frame constituting runners, and rotary teeth secured thereto.

In testimony whereof I affix my signature in presence of two witnesses.

10 EVERT ASPFORS.
